PRINTING MACHINE

Benjamin William Payne, New Mills, England, assignor to The Calico Printers' Association Limited, Manchester, England, a British company

Application March 14, 1933, Serial No. 660,763
In Great Britain March 18, 1932

4 Claims. (Cl. 101—248)

This invention relates to printing machines in which a number of printing rollers co-operate with a single impression cylinder for the purpose of printing patterns in several colours. 5
The object of my present invention is to provide improved means for effecting the relative adjustment of the printing rollers so as to ensure that the several patterns printed by the respective rollers are in fit or register accurately 10 with one another.

Heretofore the adjustment of the printing rollers has been effected by mounting the wheels (termed box wheels) driving the printing rollers upon sleeves which are connected to the mandrels 15 of the printing rollers, and by providing a driving connection between each wheel and sleeve which is adjustable to advance or retard the sleeve angularly relatively to the wheel. Such driving connection usually comprises a worm, 20 and adjustment is effected by manually turning the worm by a lever or tommy bar. This is a dangerous operation if carried out whilst the machine is running and in addition the operator whilst making the adjustment cannot see the 25 effect thereof upon the pattern.

In accordance with my present invention I provide for the adjustment of the drive to each printing roller by means which, whilst under the control of the operator, are actuated by the 30 machine drive.

My invention comprises the combination with the worm which constitutes the driving connection between the box wheel and its sleeve or hub, and which is turned about its axis only for angularly adjusting the wheel and sleeve relatively to one another, of a double wheel or two wheels carried by the box wheel and in driving connection with the worm shaft, and a further wheel coaxial with the box wheel and gearing with the 40 double wheel or two wheels carried by the box wheel either directly or through a reverse gear, with means for controlling the direct and reverse gear drive, said further wheel being normally free to rotate with the wheel with which it gears, but having means associated therewith by which its 45 rate of rotation can be controlled and so the angular adjustment of the sleeve relatively to the box wheel be effected in either a forward or a reverse direction.

50 Referring to the accompanying sheet of explanatory drawing:—

Figure 1 is a longitudinal sectional elevation and Figure 2 a cross sectional elevation on the line 1—1 of Figure 1, showing one convenient application of my invention.

The same reference letters in the two views indicate the same parts.

The box wheel *a* has the usual worm *b* mounted upon one side face, such worm meshing with a worm wheel *c* upon the sleeve or hub *d* by which the box wheel is carried. The worm shaft carries a worm wheel *e* which meshes with a worm *f* upon a shaft *g* (carried at one end by the box wheel in bearings *h*) which has a double gear wheel *i, j* thereon. The double gear wheel is adapted to be engaged by a gear wheel *k* upon a stub axle-like extension *m* of the sleeve or hub *d*. The gear wheel *k* is upon a sleeve or thimble like part *k'* movable end-wise by means of the handle *n* and splined within a brake drum *o* which forms as shown an enclosure for the various gear wheels before described. An idler gear wheel *p* which meshes with the teeth *j* of the double gear wheel upon the shaft *g* can be engaged by the gear wheel *k* when the latter is moved axially out of engagement with the wheel *i* by means of the handle *n*.

The boss of the brake drum *o* carries a spider like frame *q* secured to the box wheel by long bolts *r* and forming an outer bearing for the shaft *g*.

The brake drum *o* may have a part *s* thereof which can be conveniently gripped by hand to retard or arrest its motion. Another part *t* may serve to receive a brake block or blocks or a brake band of V form.

With the arrangement before described, if the brake drum be free to rotate, the adjustment worm *b* upon the box wheel will remain stationary upon its axis whilst rotating about the axis of the box wheel to drive the mandrel of the printing roller through the worm wheel *c* and sleeve *d*. If now the brake drum has its motion retarded or stopped, the sleeve *k'* with the wheel *k* will be retarded or stopped, which in turn will set in motion the double gear wheel *i, j*. This will cause rotation of the worm wheel *e* through the worm *f* and consequently will produce a rotation of the worm *b* about its axis to modify the rotative movement imparted to the worm wheel *c* by the said worm. If the wheel *k* is in mesh with the idler or reverse gear *p* prior to retarding or stopping the motion of the brake drum the worm *b* will be turned about its axis in reverse direction when braking occurs. Accordingly the rotation of the mandrel of the printing roller may be speeded up or retarded relatively to that of its box wheel *a*, as desired.

The brake may be actuated or applied in any convenient manner. If desired, the brake con-

trols of the several printing rollers of a machine may be brought to a common point or grouped so that the operator can make the adjustments to ensure proper register of his patterns whilst observing the printed material coming from the machine. In like manner, the controls for the gears *k* of the several box wheels may be brought together for convenience of operation.

I may vary the details of my improved adjustment control mechanism to suit any particular requirements.

What I claim is:

1. In printing machines, the combination of a box wheel, a sleeve for said box wheel, a worm wheel on said sleeve, a worm meshing with said worm wheel and constituting the driving connection between said box wheel and said sleeve and also capable of being turned about the axis of its shaft only to effect angular adjustment of said box wheel and said sleeve relatively to one another, a double gear wheel carried by said box wheel and in driving connection with said worm shaft, a reverse gear in mesh with said double gear wheel, a sleeve like part slidably mounted upon said stub axle-like extension, a further wheel co-axial with said box wheel and carried by said sleeve like part to gear directly with said double gear wheel or indirectly therewith through said reverse gear, means for imparting a sliding movement to said sleeve like part to determine whether said further wheel meshes directly or indirectly with said double gear wheel, with which it is normally free to rotate, and means associated with said further wheel by which its rate of rotation can be controlled and so the angular adjustment of said sleeve relatively to said box wheel be effected in either a forward or reverse direction.
2. In printing machines, the combination of a box wheel, a sleeve for said box wheel, a worm wheel on said sleeve, a worm meshing with said worm wheel and constituting the driving connection between said box wheel and said sleeve and also capable of being turned about the axis of its shaft only to effect angular adjustment of said box wheel and said sleeve relatively to one another, two gear wheels arranged co-axial and parallel with one another and carried by said box wheel so as to be in driving connection with said worm shaft, a reverse gear in mesh with one of said gear wheels, a further wheel coaxial with said box wheel gearing directly with the other of said gear wheels or with said reverse gear and normally free to rotate with the particular gear with which it is in mesh, means coaxial with the box wheel operable to determine whether said further wheel shall mesh directly with said gear wheel or indirectly with the other gear wheel through said reverse gear, and means associated with said further wheel, by which the rate of rotation of said further wheel can be controlled and so the angular adjustment of said sleeve

relatively to said box wheel be effected in either a forward or reverse direction.

3. In printing machines, the combination of a box wheel, a sleeve for said box wheel having a stub axle-like extension, a worm wheel on said sleeve, a worm meshing with said worm wheel and constituting the driving connection between said box wheel and said sleeve and also capable of being turned about the axis of the shaft only to effect angular adjustment of said box wheel and said sleeve relatively to one another, a double gear wheel carried by said box wheel and in driving connection with said worm shaft, a reverse gear in mesh with said double gear wheel, a sleeve like part slidably mounted upon said stub axle-like extension, a further wheel co-axial with said box wheel and carried by said sleeve like part to gear directly with said double gear wheel or indirectly therewith through said reverse gear, means for imparting a sliding movement to said sleeve like part to determine whether said further wheel meshes directly or indirectly with said double gear wheel, with which it is normally free to rotate, and a brake drum splined upon said sleeve like part and serving as a controlling means for the rate of rotation of said further wheel whereby the angular adjustment of said sleeve relatively to said box wheel can be effected in either a forward or reverse direction, said brake drum having a substantially cylindrical extension which forms an enclosure for the various parts of the mechanism.

4. In printing machines, the combination of a box wheel, a sleeve for said box wheel, a worm wheel on said sleeve, a worm meshing with said worm wheel and constituting the driving connection between said box wheel and said sleeve and also capable of being turned about the axis of its shaft only to effect angular adjustment of said box wheel and said sleeve relatively to one another, a second worm wheel on said worm shaft, a second worm upon a shaft carried by the box wheel parallelly with the axis thereof, said second worm meshing with said second worm wheel, a double gear wheel carried by said second worm shaft, a reverse gear in mesh with said double gear wheel, a further wheel co-axial with said box wheel and meshing directly with said double gear wheel or indirectly therewith through said reverse gear, means co-axial with the box wheel operable to determine whether said further wheel meshes directly or indirectly with said double gear wheel, with which it is normally free to rotate, and means associated with said further wheel by which its rate of rotation can be controlled and so the angular adjustment of said sleeve relatively to said box wheel be effected in either a forward or reverse direction.
